[57] CLAIM

The ornamental design for housing for an electronic
learning aid or game, as shown and described.

DESCRIPTION

FIG. 1 is a top plan view of a housing for an electronic
learning aid or game showing my new design;

FIG. 2 is a bottom plan view thereof;

FIG. 3 is a right side elevational view thereof; the left
side elevational view being a mirror image thereof;

FIG. 4 is a front elevational view thereof; and,

FIG. 5 is a rear elevational view thereof.

Fig. 1.Fig. 2.Fig. 3.Fig. 4.Fig. 5.
